UNITED STATES PATENT OFFICE.

JOSEPH S. STOGDALE, OF CUMBERLAND, MARYLAND.

GRATE.

Original application filed September 21, 1926, Serial No. 136,826. Divided and this application filed May 12, 1927. Serial No. 190,843.

This invention relates to improvements in grates of the reciprocal fire bar type disclosed in my prior Patent 1,574,134 granted February 23, 1926, and is a division of the subject matter set forth in my co-pending application, Serial Number 136,826 filed September 21, 1926.

The principal purpose of the present invention is to provide an improved design of fire bar including removable grate sections capable of being applied or removed with greater facility than the grate sections associated with the fire bars disclosed in my prior patent.

Other purposes, advantages and characteristic features of the invention will be more readily understood from the following detailed description and accompanying drawings, in which,

Figure 1 is a top plan view of a fire bar equipped with removable grate sections in accordance with the present invention.

Figure 2 is a side elevation of the construction shown in Figure 1.

Figure 3 is a longitudinal sectional view and,

Figure 4 is a transverse sectional view.

Preliminary to discussing the specific construction of the fire bar disclosed herein it may be explained that in actual practice a number of these fire bars are arranged in spaced parallelism upon a suitable support and reciprocated through the instrumentality of a suitable operating mechanism. This arrangement and operation of the fire bars is covered in my co-pending application and further disclosure thereof is not deemed necessary to an understanding of the structure to which the present invention is directed.

As shown in the drawings the fire bar consists of a rectangular frame 12 closed at the top by a plurality of inserted grate sections

13 arranged end to end as shown in Figure 3 and provided with terminal supporting flanges 14 resting on the supporting surfaces 15 afforded by the upper edges of the end members of the frame and the intermediate bridges 16 connecting the sides of the frame. This arrangement obviously permits the grate sections 13 to be readily applied and removed.

As shown to advantage in Figure 3 the upper edge of frame 12 forms a continuous guard flange 17 projecting above the supporting surfaces 15 and having its upper surface flush with the upper surface of the inserted grate sections. This guard flange serves to protect the terminal flanges 14 and the sides of the inserted grate sections.

Having thus disclosed what I now conceive to be the preferred embodiment of the invention it will be understood that the various changes in the construction and arrangement of parts may be resorted to within the scope of the invention as defined by the appended claim.

What I claim is:

A grate of the character described comprising an open rectangular frame having side and end members of equal height, said end members being recessed at their inner upper edges to provide horizontal supporting surfaces below the upper plane of the frame, spaced bridge members connecting the sides of the frame and having their upper edges disposed in the plane of said horizontal surfaces and a plurality of grate sections arranged in the frame in end to end relation and provided with terminal flanges supported by said horizontal supporting surfaces and the upper edges of the bridge members.

In testimony whereof I hereunto affix my signature.

JOSEPH S. STOGDALE.
